UNITED STATES PATENT OFFICE.

BENJAMIN E. NORVELL, OF PASADENA, CALIFORNIA.

LIGHT.

Application filed October 31, 1923, Serial No. 671,976. Renewed March 21, 1925.

To all whom it may concern:

Be it known that I, BENJAMIN E. NORVELL, a citizen of the United States, residing at Pasadena, in the county of Los Angeles and State of California, have invented new and useful Improvements in Lights, of which the following is a specification.

This invention relates to a lighting device, the general object of the invention being to provide means for causing the rays of light to pass in any desired direction or in all directions, as desired.

Another object of the invention is to provide a plurality of shutters on each side of the device with individual means for operating the shutters of each set and with other means associated therewith for operating all the shutters simultaneously.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is an elevation of the device with the shutters closed.

Figure 2 is a sectional view with the shutters of one set open and the other set closed.

Figure 3 is a similar view with all the shutters open.

Figure 4 is a section on line 4—4 of Figure 2.

Figure 5 is a plan view of the spider 15.

In these views, 1 indicates a base, 2 four corner bars of angle shape having their ends connected with the base and 3 indicates a top piece connected with the upper ends of the bars. The sides of the device are composed of a plurality of shutters 4 which have trunnions 5 on their ends, located a short distance from the upper edge of each shutter, engaging the corner bars so that the shutters are pivotally supported by the said bars. These shutters will overlap when in closed condition so as to prevent the escape

of the light rays from the lamp 6 which is carried by the base and which may be of any desired type. Each shutter is provided with a curved arm 7, the outer end of which is pivoted to a bar 8, the pivot pin 9 passing through a slot 10 in the bar. Each bar is connected with the shutters forming one side of the device so that when the bar is moved the shutters at one side of the device will be actuated. The bars are guided in openings in the base and top piece and the upper end of each bar is provided with a knob 11 so that it can be moved by hand. A short bar 12 passes through the top piece and through a pyramid 13 carried by said top piece, the upper end of the bar being provided with a knob 14 so that it can be adjusted vertically, and its lower end carries a spider 15, the ends of which being provided with projections 16 which engage slots 17 in the bars 8 so that when the bar 12 is moved upwardly all the bars 8 will be also raised to close all the shutters and when the bar 12 is moved downwardly all the shutters will be open. It will thus be seen that the shutters of one set can be opened or closed, or partly opened by means of the bar 8 connected with such set or all the shutters can be adjusted simultaneously by means of the bar 12 and its associated parts. Thus the rays of light can be directed in different directions or in all directions or the rays of light can be entirely cut off by closing all the shutters.

The device can be used for different purposes such as lamps used in different situations, a lantern and other devices where it is necessary or desirable to control the rays of light passing therefrom.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A device of the class described comprising a casing, a lamp therein, a set of shutters at each side of the casing, a curved

arm on each shutter, a rod to which the arms of each set of shutters are connected and means for reciprocating the rods.

2. A device of the class described comprising a casing, a lamp therein, a set of shutters at each side of the casing, a curved arm on each shutter, a rod to which the

arms of each set of shutters are connected, means for reciprocating the rods, a spider having parts engaging slots in the rods and 10 a vertically movable rod arranged in the top of the casing and connected with the spider.

In testimony whereof I affix my signature.
BENJAMIN E. NORVELL.
